UNITED STATES PATENT OFFICE

162,873

HYDRAULIC TRENCHER

John S. Pilch, Ware, Mass.

Application December 14, 1949, Serial No. 6,602

Term of patent 14 years

(Cl. D14—3)

To all whom it may concern:

Be it known that I, John S. Pilch, a citizen of the United States and resident of Ware, in the county of Hampshire and State of Massachusetts, have invented a new, original, and ornamental Design for Hydraulic Trencher, of which the following is a specification, reference being had to the accompanying drawings, forming part thereof.

Fig. 1 is a side view of a hydraulic trencher, embodying the design;

Fig. 2 is a side view thereof taken from the opposite side;

Fig. 3 is a top or plan view thereof; and

Fig. 4 is a perspective view thereof.

In the drawings the characteristic features of my design are shown in full lines.

I claim:

The ornamental design for a hydraulic trencher, substantially as shown and described.

JOHN S. PILCH.
